GARMENT HANGER

Otto B. Mantell, 200 W. 59th St.,
New York, N.Y. 10019

Filed June 4, 1968, Ser. No. 12,199

Term of patent 14 years

U.S. Cl. D80—8
Int. Cl. D6—07

FIG. 1

FIG. 2

FIG. 3

FIG. 4

FIG. 5

FIG. 6

I claim:

The ornamental design for a garment hanger, as shown.
